LIQUID TREATMENT OF TEXTILE MATERIALS AND THE LIKE

Albert J. Pfeiffer, Port Washington, N. Y., and Thayer P. Gates, Providence, R. I.

Application June 5, 1930. Serial No. 459,372

5 Claims. (Cl. 8—18)

This invention relates to liquid treatment of textile material and the like and more particularly to a method of and means for effecting thorough and expeditious penetration of the textile material by the treating liquid.

Although the invention is applicable to different kinds of material and may be carried out in different ways, it is especially applicable to the treatment of raw silk preparatory to the throwing operation and, for convenience, will be described in connection with this operation. Heretofore it has been the general practice to take the packages of raw silk as received, enclose them in bags, and place them in open vats containing emulsions of soap and oil which act to render the silk sufficiently pliable for working. The silk is left in the emulsion from twelve to fourteen hours and even then the degree of penetration and uniformity of results are not entirely satisfactory.

The effectiveness of this liquid treatment of the silk may be indicated with considerable accuracy by the color effect produced by tinting material, in the form of a fugitive dye, which is commonly used for identifying the silk after it has been wound on cops or other devices on which the silk is wound. When the silk is treated in a vat with an emulsion containing the tinting material, the latter is taken up slowly by the silk and, upon inspection of the silk, it will be seen that the tint is not taken uniformly. According to the present invention the treatment of the silk by the emulsion may be effected in a comparatively short time, say two hours, and the treatment is substantially uniform, as will be indicated by the uniformity of the tinting if tinting material is used in the emulsion.

An important object of the invention is to provide an improved method of liquid treatment of the character specified. Another important object of the invention is to provide means for carrying out the method.

Other objects and advantages will appear upon consideration of the following detailed description and of the drawings, in which:

Fig. 1 is a front elevation of one embodiment of the invention;

Fig. 2 is a fragmentary side view;

Fig. 3 is a diagrammatic view illustrating the operation of the apparatus; and

Fig. 4 is a fragmentary vertical section showing details of construction.

The objects of the invention may in general be attained by maintaining a mass of the materials in a definite position and subjecting it to

the action of the treating liquid under pressure, as by forcing the treating liquid therethrough. In a more specific form of the method, the treating liquid may be forced through the mass in different directions at different times, for example, the direction of movement of the liquid through the mass may be reversed at intervals. The preferred apparatus for carrying out the invention includes a container (of the same general nature as a kier) having a central vertical casing to receive the material to be treated, devices engaging the material from above and from below to prevent vertical movement thereof while permitting passage of the treating liquid, and outside fluid tight connections between the bottom of the central casing and the top thereof to form a closed path for the fluid when forced through the mass of material. The apparatus may also include means for circulating the liquid so as to pass the treating liquid alternately in opposite directions through the material to be treated. It will be apparent that considerable pressure may be necessary to force the treating liquid through the material to be treated.

Referring to the drawings, 10 designates a cylinder of suitable material resting on a bottom plate 11 and provided at a higher level with an openwork support 12 for the material, such as raw silk, placed in the cylinder. The open work support 12 is preferably in the form of a plate having perforations of suitable size and the edges of said perforations are finished so as to avoid damage to the silk or other material to be treated. In view of the fact that the silk to be treated comes into direct or substantially direct contact with the surfaces of the cylinder 10 and support 12, these parts which are preferably of metal or metal alloy, should be made of material capable of resisting corrosion by the liquid. Otherwise the silk would be in danger of discoloration by contact therewith. The plate 12 is supported by suitable means, here shown as angles 13 welded to the cylinder 10 and to the plate at its lower side. The connection between the lower edge of the cylinder 10 and the bottom plate 11 should be fluid tight and strong and preferably is produced by welding.

In order that the treating liquid or emulsion may be forced continuously through the cylinder 10 in either one direction or the other, it is necessary to provide an outside connection between the upper and lower ends thereof. This may be done in different ways but preferably by means of an outer cylindrical metal shell 14 connected at its bottom with the plate 11, as by a fluid tight

welded joint, and extending above the upper end of the cylinder 10. Obviously exchange of liquid between the upper part of the cylinder 10 and the upper part of the annular chamber enclosed by 5 the outer shell may be effected over the upper edge of the cylinder 10, which edge, it may be said in this connection, is rounded to avoid damage to material inserted from above. The connection between the lower part of the cylinder 10 and the annular chamber surrounding the 10 same will be described hereinafter.

The cylinders or shells 10 and 14 are subjected to heavy stresses and the inner cylinder 10 is reinforced not only by the plate 12 but also by 15 spacers 15 of strap iron connecting the upper end thereof with the cylinder or shell 14. Preferably the ends of these spacers extend perpendicularly from the main bodies thereof and are connected with said cylinders or shells by 20 welding. The outer shell 14 is illustrated as reinforced at its lower end by an annulus or ring 16 of angle metal having an inwardly projecting horizontal flange engaging the bottom plate 11 and an upwardly projecting flange engaging 25 the outer surface of the shell 14, and at its upper end by an annulus or ring 17 having a downwardly extending flange engaging the outer surface of the shell and an outwardly projecting horizontal flange 18. Preferably both of the rings 16 30 and 17 are secured in position by welding.

The apparatus is illustrated as supported in raised position above the floor or ground by means of a stand made of strap iron and having legs 19. At the top of each leg the metal strap 35 is bent down to present a part on which the horizontal flange of the ring 16 rests. To fasten the metal straps to the ring 16 at such points, the lower flange of the ring 16 is supplied with flat head cap screws 20 inserted from above 40 through suitable openings so that in their final positions the heads will lie flush with the upper surface of the flange. These screws may be threaded into the metal straps adjacent the upper ends of the legs or may pass through openings in the straps and be provided at their lower ends with nuts to clamp the parts together.

At its top the apparatus is provided with a strong cover 21 having an annular rim overlying the flange 18 and resting on a ring 22 of 50 packing material held in a metal channel 23 arranged in a ring at the inner edge of the flange 18 and secured thereto by a fluid tight weld. The cover should be clamped tightly in closed position during operation of the apparatus and to 55 this end it is reinforced at its outer edge by a metal ring 24. The clamping may be effected in any suitable manner and, as here illustrated, this is done by providing at suitable intervals around the flange 18 eye bolts 25 pivotally mounted at their eyes on a rod 26 arranged in annular form and held in position at the lower surface of the flange. To accommodate the eye bolts, the flange 18 is provided with slots 27 extending 60 to its edge and corresponding slots 29 are 65 provided in the cover and the reinforcing ring 24. Threaded on the upper ends of the eye bolts are nuts 30 of considerable height and provided adjacent to their upper ends with cross pieces 31 to facilitate the turning thereof by hand. This 70 arrangement enables the cover to be clamped down tightly while at the same time the cover can easily be released for removal by loosening the nuts 30 and swinging the eye bolts outwardly beyond the outer ends of the slots 29.

75 The material is placed in and removed from the

cylinder 10 while the cover 21 is off. As will be brought out more clearly hereinafter, it is necessary to hold the material in position during treatment. To this end use is made of an open-work member 32, preferably a perforated plate similar to the supporting plate 12, suspended from the cover 21 by spacers 33, similar to spacers 15, which serve to press the plate 32 down against the contents of the cylinder 10 and hold them in position during the treating operation.

The connections at the lower part of the apparatus will now be described. As best seen in Figs. 1 and 3, the annular chamber between the shells 10 and 14 is connected at the right hand side with a downwardly extending conduit or pipe 34 and at the left hand side with a corresponding conduit or pipe 35 and from pipes 34 and 35, generally horizontal pipes or conduits 36 and 37, respectively, extend to three-way valves 38 and 39. The valve 38 may be turned to a position to connect the pipe 34 with the inlet of a centrally positioned pump 40 and shut off a pipe 41 connecting the valve with the lower end of the cylinder 10 beneath the perforated plate 12, or to a position to close the connections 190 between the pipe 34 and the pump and also the pipe 41 and to establish a connection between the pipe 41 and the inlet end of the pump 40. The valve 39 may be turned to connect the outlet of the pump with a pipe 42 connected with the 195 lower part of the cylinder 10 and to close the connection with the pipe 35, or to close the connection with the pipe 42 and connect the pipe 35 with the outlet of the pump.

In order to operate the two valves 38 and 39 110 simultaneously, arms 43 and 44 are secured to the stems of these valves and these arms are connected by means of a link 45, and for convenience the operation of the valves may be effected by means of a handle 46 at the front of 115 the apparatus. As here shown the handle 46 is secured at its lower end on a shaft 47 rotatably mounted in a fixed bracket 48 at the lower side of the ring 16, and fixed on the shaft is a downwardly extending arm 49 provided with a longitudinal slot to receive a pin 50 projecting from the link 45. Referring to Fig. 3, it will be seen that, when the handle 46 is in its right hand position, the pump draws liquid downwardly through the pipe 41 and forces it upwardly 120 through the pipe 35, and that, when the handle is in its left hand position the pump will draw liquid down through the pipe 34 and force it up through the pipe 42. In the first case, the pump 40 will produce a vacuum beneath material packed tightly in cylinders 10 and pressure of liquid at the upper side of the material. In the second case, a vacuum will be produced at the top of the cylinder 10 and pressure at the bottom thereof. In each case, the vacuum on 130 one side and pressure on the other will act together to force liquid through the material to be treated.

Preferably the pump 40 is of the rotary type and is driven by an electric motor 51 through a 140 shaft 52 common to them. The liquid or emulsion may be supplied in any suitable manner, and as indicated in Fig. 1 is supplied to the upper part of the apparatus through a pipe or line 53 controlled by a valve 54. Inasmuch as 145 the pipe 53 enters the cylinder or shell 14 below the cover, air will be trapped in the upper part of the apparatus but may be forced out through a suitable air vent device 55 provided in the cover. The apparatus may be drained through an exten- 150

- sion of the pipe 34, which extension is normally closed by means of a drainage valve 56. For convenience in handling the cover 21, it is provided with handles 57 arranged symmetrically thereon.
- 5 In operation, high pressures are developed in the upper part of the apparatus and a vacuum in the lower part thereof when the liquid is forced downwardly through the material in the inner cylinder 10, and high pressures are developed in 80 the lower part of the inner cylinder and a vacuum in the upper part thereof when the liquid is forced upwardly through the material. It is desirable to be able to observe from time to time the pressure being developed so that when 85 10 an excessive pressure is maintained the motor can be stopped. To this end, the apparatus is provided at its front and adjacent to the top thereof with two pressure gauges 58 and 59 arranged with the gauge 58 directly above the 90 20 gauge 59, the upper gauge 58 being connected by means of a pipe or line 60 with the upper part of the cylinder 14 and the lower gauge 59 being connected with lower part of the cylinder 10 by means of a pipe or line 61.
- 25 In recapitulation, the operation is substantially as follows: Assuming that the cover 21 is off, the first step is to place the proper amount of material to be treated, silk for example, in the inner cylinder 10. The cover 21 is then placed 100 30 in position and clamped down tightly by means of the nuts 30, the perforated plate 32 engaging the silk at the top and holding it firmly in position on the perforated plate or support 12. With the drainage valve 56 closed, the treating liquid 105 35 or emulsion is supplied through the pipe 53 and the open valve 54 until the apparatus is substantially full, the air being vented through the vent device 55. After closing the valve 54, the motor 110 51 is started and the pump 40 is operated thereby.
- 40 Assuming the valves 38 and 39 to be positioned as shown in Fig. 3, the liquid will be drawn downwardly through the cylinder 10 and thence through the pipe line 41 to the pump 40 which forces the liquid through the valve 39 and the 115 45 pipe line 35 to the annular chamber between the shells 10 and 14 and eventually over the top of the cylinder or shell 10 and downwardly therethrough. Upon throwing the handle 46 to the left, the direction of movement of the liquid 120 50 through the material will be reversed. The handle may be thrown back and forth at suitable intervals and the treatment continued until the desired degree of treatment has been attained. Experience shows that more satisfactory results 125 55 are obtained and in a very much shorter time than by the treatment heretofore in general use.
- It should be noted that the apparatus is self-contained—that is, is built in a single unit—and that the silk or material being treated is held firmly in position thus preventing tangling. Also the liquid is circulated in a closed circuit in that during operation of the apparatus all of the liquid is in circulation although in either of 130 60 two directions.
- 65 It should be understood that various changes may be made in the construction and arrangement of parts and that certain parts may be used without others without departing from the true spirit and scope of the invention.
- 70 Having thus described our invention, we claim:
1. In apparatus for liquid treatment of textile material, the combination of an upright container, means for holding the material therein, and means for selectively subjecting said material to a vacuum at one side and to pressure at 140 75 the other including a pump, means for connecting the ends of the container including two connections with one end of the container, a three-way valve in each of said connections one being connected with the inlet of the pump and the other with the outlet, and means for operating both of said valves simultaneously so as to draw liquid from one end of said container under a vacuum through one of the two connections and force it into the other end of the container or to force the liquid into the first mentioned end of said container through the other of said connections and to withdraw it under vacuum from said other end of the container. 80
  2. In apparatus for liquid treatment of textile material and the like, the combination of a cylinder to receive said material, an open work support for the material in said cylinder, an outside cylinder extending above the inner cylinder to provide for flow of liquid over the upper edge of the inner cylinder, a cover for the outer cylinder, means for introducing the liquid into the outer cylinder through its wall, an air vent in the cover, and means for selectively subjecting said material to a vacuum at one side and to pressure 90 95 at the other side a pump at the bottom of the apparatus, a three-way valve connected with the outlet of the pump and arranged to connect said outlet either with the interior of the inner cylinder or with the space between the inner and outer cylinders, a three-way valve connected with the inlet of the pump and arranged to connect the same with the interior of the inner cylinder or with the space between the cylinders, and means for controlling said valves simultaneously 100 105 to effect a flow of liquid either downwardly through the inner cylinder or upwardly therethrough. 110
  3. In apparatus for liquid treatment of textile material and the like, the combination of a cylinder to receive said material, an open work support for the material in said cylinder, an outside cylinder extending above the inner cylinder to provide for flow of liquid over the upper edge of the inner cylinder, a cover for the outer cylinder, means attached to said cover for engaging said material and holding it down on said support, and means for selectively subjecting said material to a vacuum at one side and to pressure at the other side including a pump at the bottom 115 120 125 of the apparatus, a three-way valve connected with the outlet of the pump and arranged to connect said outlet either with the bottom of the interior of the inner cylinder or with the lower end of the space between the inner and outer cylinders, a three-way valve connected with the inlet of the pump and arranged to connect the same with the interior of the inner cylinder or with the space between the cylinders, and means for controlling said valves simultaneously to effect a flow of liquid either downwardly through the inner cylinder or upwardly therethrough. 130 135
  4. In apparatus for liquid treatment of textile material and the like, the combination of a cylinder to receive said material, an open work support for the material in said cylinder, an outside cylinder extending above the inner cylinder to provide for flow of liquid over the upper edge of the inner cylinder, a cover for the outer cylinder, and means for selectively subjecting said material to a vacuum at one side and to pressure at the other side including a pump at the bottom of the apparatus, a three-way valve connected with the outlet of the pump and arranged to connect said outlet either with the bottom of 140 145 150

the interior of the inner cylinder or with the lower end of the space between the inner and outer cylinders, a three-way valve connected with the inlet of the pump and arranged to connect the same with the interior of the inner cylinder or with the space between the cylinders, a handle and means operable by said handle for controlling said valves simultaneously to effect a flow of liquid either downwardly through the inner cylinder or upwardly therethrough.

5. In apparatus for liquid treatment of textile material, the combination of an upright container, means for holding the material therein, and means for selectively subjecting said material to a vacuum at one side and to pressure at the other including a pump having an inlet and an outlet, means for connecting the ends of the container including two connections with one

end of the container, one of said connections being connected at an intermediate point with said inlet to form a three-way connection and the other of said connections being connected at an intermediate point with said outlet to form a three way connection, valve means at each of said three way connections, and means for operating said valve means substantially simultaneously so as to draw liquid from one end of said container under a vacuum through one of the two end connections and force it into the other end of the container or to force the liquid into the first mentioned end of said container through the other of said end connection and to withdraw it under vacuum from said other end of the container.
